(57) **CLAIM**

The ornamental design for a vertical transaction card, as shown and described.

DESCRIPTION

The patent or application file contains at least one drawing executed in color. Copies of this patent or patent application publication with color drawing(s) will be provided by the Office upon request and payment of the necessary fee. Color is an aspect of the front and back of the vertical transaction cards of the present design as shown in FIGS. 1, 2 and 5. FIG. 1 is a front elevation view of the vertical transaction card with an embedded diamond on the top left corner, showing my new design;

FIG. 2 is a rear elevation view thereof;

FIG. 3 is a left-side elevational view of FIG. 1, the right-side elevational view being a mirror image thereof;

FIG. 4 is a bottom plan view of FIG. 1, the top plan view being a mirror image thereof;

FIG. 5 is an enlarged front elevation view taken from the circumscribed area of FIG. 1 marked FIG. 5; and,
FIG. 6 is a front sectional view taken along line 6-6 from the enlarged area described in FIG. 5.

The broken line showing portions of the vertical transaction card is included for the purpose of illustrating environmental structure and forms no part of the claimed design.
